UNITED STATES PATENT OFFICE.

CHARLES THOMAS BROCK SANGSTER, OF BIRMINGHAM, ENGLAND.

DESIGN FOR A BICYCLE-FRAME.

SPECIFICATION forming part of Design No. 34,253, dated March 19, 1901.

Application filed February 21, 1901. Serial No. 48,377. Term of patent 3½ years.

To all whom it may concern:

Be it known that I, CHARLES THOMAS BROCK SANGSTER, general manager of The Cycle Components Manufacturing Company, Limited, a subject of the King of Great Britain, residing at Bournbrook, Birmingham, England, have invented and produced a new and original Design for a Bicycle-Frame, of which the following is a specification.

10 The drawing represents a perspective view of my new and original design for a bicycle-frame.

The leading or material feature of my design consists in the novel arrangement of the 15 tubes *a* and *b*, disposed between the head *c* and the seat-tube *d*. The tube *a* is directed diagonally from the seat-lug at the summit of the tube *d* to a lug at the bottom of the head *c*, and the tube *b* is directed also diagonally from a lug at the top of the said head 20 to a lug or junction *d'*, carried on the seat-tube a distance below the middle. The tube *b* intersects the tube *a* at the point *e* nearer to the head than to the seat-tube and at which 25 a four-way junction-lug is provided, while a

further essential feature to the present design is that the said tube *b* runs parallel to the front diagonal frame-tube *f*, extending from the head to the crank-axle-bearing bracket *g*.

The frame is provided in the back part with backstays *h* and chain-stays *i*, as usual, and, further, to strengthen the tube *d* at the point of its connection with the diagonal member *b* a pair of stays *j* are disposed diagonally 35 between the lug *d'* and the rearward ends of the chain-stays *i*.

Having described my invention, what I claim as new, and desire to secure by Letters Patent, is—

30 The design for a bicycle-frame as herein described and shown.

In testimony whereof I have hereunto set my hand in presence of two subscribing witnesses.

CHARLES THOMAS BROCK SANGSTER.
